(57) CLAIM

The ornamental design for a claw clip, as shown and described.

DESCRIPTION

FIG. 1. is a front perspective view of the claw clip;
FIG. 2 is a left side view of the claw clip, the right side view is a mirror image of the left side;
FIG. 3. is a top view thereof;
FIG. 4. is a bottom view thereof;
FIG. 5. is a front view thereof; and,
FIG. 6. is a rear view thereof.

The broken lines showing a portion of the claw clip are for illustrative purposes only and do not form part of the claimed design.
